(57) **CLAIM**

The ornamental design for a wireless link adapter, as shown and described.

DESCRIPTION

FIG. 1 is a Top Rear Right Perspective view of a wireless link adapter; (Embodiment 1)

FIG. 2 is a Bottom Rear Right Perspective view (Embodiment 1)

FIG. 3 is a Front view (Embodiment 1)

FIG. 4 is a Rear view (Embodiment 1)

FIG. 5 is a Left view (Embodiment 1)

FIG. 6 is a Right view (Embodiment 1)

FIG. 7 is a Top view (Embodiment 1)

FIG. 8 is a Bottom view (Embodiment 1)

FIG. 9 is a Top Rear Right Perspective view of a wireless link adapter; (Embodiment 2)

FIG. 10 is a Bottom Rear Right Perspective view (Embodiment 2)

FIG. 11 is a Front view (Embodiment 2)

FIG. 12 is a Rear view (Embodiment 2)

FIG. 13 is a Left view (Embodiment 2)

FIG. 14 is a Right view (Embodiment 2)

FIG. 15 is a Top view (Embodiment 2)

FIG. 16 is a Bottom view (Embodiment 2)

FIG. 17 is a Top Rear Right Perspective view of a wireless link adapter, with a circular portion stipple shaded to represent a contrast in appearance in the stippled portion (Embodiment 2);

FIG. 18 is a Bottom Rear Right Perspective view (Embodiment 2)

FIG. 19 is a Front view (Embodiment 2)

FIG. 20 is a Rear view (Embodiment 2)

FIG. 21 is a Left view (Embodiment 2)

FIG. 22 is a Right view (Embodiment 2)

FIG. 23 is a Top view (the broken line circle with numeral “25” indicates that FIG. 25 illustrate a magnification of a portion of FIG. 23) (Embodiment 2)

FIG. 24 is a Bottom view (Embodiment 2); and,

(Continued)

FIG. 25 (Embodiment 2) illustrates partial view of the complete device shown in other figures. FIG. 25 also illustrates a portion which is an illumination window. The features shown in broken lines depict environmental subject matter only and form no part of the claimed design. The dot-dash broken line circles depict the limits of the enlarged view and form no part of the claimed design.

1 Claim, 16 Drawing Sheets
